UNITED STATES PATENT OFFICE.

GEORGE E. PETERSEN, OF BRISTOL, PENNSYLVANIA.

ANTIGLARE DEVICE FOR LAMPS.

Application filed October 30, 1922. Serial No. 597,763.

To all whom it may concern:

Be it known that I, GEORGE E. PETERSEN, a citizen of the United States, and a resident of Bristol, county of Bucks, State of Pennsylvania, have invented a certain new and useful Improvement in Antiglare Devices for Lamps, of which the following is a specification.

Some of the objects of the present invention are to provide an improved anti-glare or dimming device for lamps which reflect or project rays of light in a desired direction; to provide means for deflecting the projected light rays of a lamp, or permitting such rays to travel uninterrupted at the will of the user of the lamp, or the driver of the vehicle to which the lamp is attached; to provide an improved anti-glare mechanism which can be applied to head lamps in use or can be built into such a lamp at the time of manufacture; to provide a shutter mechanism for head lamps whereby the direct rays or those producing glare can be deflected without materially diminishing the illumination in the vicinity of the lamp; to provide a plurality of relatively fixed shutters arranged to swing about a common axis in a manner to regulate at will the light rays emanating from a lamp; and to provide other improvements as will hereinafter appear.

In the accompanying drawings, Fig. 1 represents a front elevation of a head lamp equipped with a shutter mechanism embodying one form of the present invention; Fig. 2 represents a side elevation of the same showing in dotted lines a second position of the device; Fig. 3 represents a modification of the attaching means for the device; and Fig. 4 represents a side elevation of the same.

Referring to the drawings, one form of the present invention is shown as applied to a motor vehicle lamp 10, of well known construction having a body 11 and a flanged band 12 attached thereto and serving as a mounting for the lens 13. In general the lamp casing 11 or its reflector parts are of parabolic shape to reflect the light rays in parallel relation in front of the lamp as will be understood.

For the purpose of intercepting such parallel reflected light rays at desired times to

break the glare therefrom and to deflect such rays in a manner to continue to illuminate the path of the vehicle, a plurality of shutters 14 are provided, which are arranged in superposed slightly inclined parallel relation and all fixed at their respective ends to a ring or a flanged ring 15, which has a diameter sufficient to encircle the band 12 of the lamp 10. Preferably the width of the flange 15 tapers downwardly so that the flange becomes gradually narrower and terminates in a relatively thin lower marginal edge. This construction serves to prevent the light rays from being cut off around the lower and bottom portion of the lamp and thereby increases the illumination of the roadway.

In order to mount the ring 15 for swinging movement relative to the lamp 10, the band 12 is provided with two outwardly projecting pivot pins or studs 16, preferably located at horizontally, diametrically opposite points to function as bearings to support opposite sides of the flanged ring 15. Suitable nuts or heads 17 cooperate with the respective pins 16 to retain the ring 15 properly held for pivotal or swinging movement on the said pins. While the aforesaid pins 16 are here arranged diametrically opposite, it is to be understood that the invention is not limited to the exact location of the axis of rotation of the ring 15. The shutters 14 are arranged in parallel relation but angularly disposed with respect to the plane of the ring 15, the arrangement being such that in a dimming position the shutters 14 are inclined downwardly and each has a width such that the outer edge thereof projects below the inner edge of the next lower shutter. This causes the direct rays of light from the lamp to be deflected downwardly and thereby eliminates all rays of a glaring nature from the vision of anyone approaching the lamp from the front. Furthermore the lower face of each shutter 14 is preferably treated by nickel plating or otherwise to provide a light reflecting surface so that the maximum luminosity of the downwardly deflected rays is obtained. The upper surface of each shutter 14 is painted or otherwise coated with light absorbing material in order to prevent any of the downwardly deflected rays

from being again reflected forward or into the path of anyone in front of the lamp.

As a means for holding the ring 15 in a position so that the shutters 14 cut off the glare and serve as a dimmer, a spring 18 is provided, one end of which is attached to a rigid bracket strip 20 secured to the lamp band 12, while its other end is secured to a lug 21, or other part formed on the flanged ring 15. In this position the shutters 14 intercept the parallel rays, which are forwardly projected, and reflect them downwardly, thereby eliminating all glare but still giving a relatively brilliant illumination of the roadway for a considerable distance ahead and to both sides of the lamp or lamps.

For causing the ring 15 to be swung to a position in which the shutters 14 are in an approximately horizontal position, a split clamping lug 22 is formed upon one side of the flanged ring 15 to receive an end of a cross-rod 23, which extends to and is connected to a shutter ring 15 on the companion lamp at the opposite side of the vehicle. An operating wire or rod 24 is fixed at one end to the cross-rod 23 and has its other end brought to a convenient location within easy reach of the driver of the vehicle where it can be operated at will to control the actuation of the shutters 14. When the rod 24 is moved to shift the shutter ring 15 to normal position, as indicated in dotted lines Fig. 2, it is fastened to a suitable fixed part in any well known manner to hold the shutters against the tension of the spring 18. By releasing the rod 24 the shutter mechanism is automatically shifted to dimming position by the action of the spring 18 and the parts are firmly held against vibration and rattle.

Where the anti-glare device is not constructed as a part of the lamp with which it is to be used, but is to be attached to a head lamp in use, a split ring clamp 28, shown in Fig. 3, is provided, which is arranged to fit over the lamp barrel or casing and be rigidly secured thereto by a bolt 30 or other fastening means. Two oppositely located laterally projecting pins 31 are fixed to the ring clamp 28 to serve as the bearing supports for the shutter ring 15 in the same manner as do the pins 16 of the built in type of shutters.

The operation of the device is as follows:—Under normal running conditions, the rod 24 is temporarily secured at its free end from the driver's seat, so that the ring 15 is held in the position shown in dotted lines Fig. 2, with the shutters approximately horizontal and the rays of light from the lamp are unobstructed and have their full lighting value for a considerable distance in front of the lamp. When an approaching person or vehicle comes within

the field of the projected rays, the rod 24 is released and the spring 18 then functions to swing the ring 15 to the position shown in full lines Fig. 2. This causes all the shutters 14 to move simultaneously to the inclined position to intercept all forwardly projected direct light rays from the lamp and deflect them angularly and in a direction to strike the roadway at an acute angle. The result is a relatively wide diffusion of light upon the road to provide a safe driving range for the operation of the vehicle, while to the approaching vehicle the diffused light serves as a safe guide without any glare from the lamp.

It should be noted that the present dimmer device is widely different from the complicated shutter type of dimmers heretofore suggested in the art in that all of the present shutters are a unitary rigid construction having a common axis of rotation. This construction gives a single movable part to be controlled, thereby affording positive action in either position, and also eliminates vibration and rattle. While the operating means are here controlled manually it is to be understood that electro-magnetic means or any other means may be employed to cause shifting of the shutters without departing from the invention.

Having now fully described my invention, what I claim is:—

1. The combination with a lamp, of a flanged ring pivotally mounted thereon for rocking movement, a plurality of parallel downwardly inclined shutter slats carried thereby for downward deflection of light rays, means for rocking said ring to cause said shutter slats to assume a position parallel to the direct rays of the lamp, and the flange of said ring being tapered to an extreme narrow lower marginal edge to permit the light rays to be projected between the ring and the bottom portion of the lamp when the ring is in normal position.

2. The combination with a lamp, a ring frame pivotally connected at its center to the lamp casing, a plurality of parallel downwardly inclined shutter slats fixed to said ring frame, means for normally holding the ring frame at an angle to the face of the lamp with its lower edge abutting the lower edge of said lamp face to cause the slats to deflect the rays of the lamp downwardly, and means to move said frame to a position with its upper edge overlapping the upper edge of the lamp face to cause said slats to assume a position parallel with the direct rays from said lamp.

3. The combination with a lamp, of a band clamp arranged to fit over and be secured to the body of a lamp, a ring frame connected at its horizontal axis to said band clamp, a plurality of parallel downwardly inclined shutter slats fixed to said ring

frame, means for normally holding the ring frame at an angle to the face of said lamp to cause said slats to deflect the rays of lamp downwardly, and means to move said frame 5 to a position with its upper edge portion overlapping the upper edge portion of the band clamp to cause said slats to assume a

position parallel with the direct rays from said lamp.

Signed at Philadelphia, county of Philadelphia, State of Pennsylvania, this 23 day of October, 1922.

GEORGE E. PETERSEN.
